Ward Crosby & Smith

UNITED STATES PATENT OFFICE

GEORGE E. CONNOLLY, OF OAKLAND, CALIFORNIA, ASSIGNEE TO NICHOLS COPPER COMPANY, OF NEW YORK, N. Y., A CORPORATION OF NEW YORK

FURNACE RABBLE ARM AND TOOTH CONSTRUCTION

Application filed March 5, 1927. Serial No. 173,145.

This invention relates to furnace rabble arms and teeth and has among its objects the provision of an improved, durable and light weight construction for the desired purposes.

Various other specific objects, features and advantages will more clearly appear from the detailed description given below taken in connection with the accompanying drawings 10 which form a part of this specification.

In the drawings, Fig. 1 is a transverse sectional view of a rabble arm showing a rabble tooth attached thereto according to this invention;

15 Fig. 2 is a longitudinal sectional view of the construction such as shown in Fig. 1; and

Fig. 3 is a view similar to Fig. 2, but showing a modified form of construction.

In Figs. 1 and 2 the main body portion or 20 housing of a rabble arm is indicated at 10 and within the same a cooling fluid conduit as at 11 may be enclosed. Along the lower side of the member 10 a plurality of rabble teeth as at 12 may be mounted at intervals.

25 Each of the rabble teeth may comprise a portion having a substantially vertical area 13 for engagement with the ore which is to be rabbled. Along the upper edge of this area a suitable tongue or tenon portion 14 is provided for cooperating with and slidably joining a correspondingly grooved portion at the under side of the rabble arm comprising a pair of depending flanged members as at 15 and 16. The flanged members 15 and 16 are 30 preferably cast integral with the lower wall of the rabble arm housing 10 and follow as closely as possible the curved contour of this housing. In the example shown, the rabble arm housing is of a cylindrical shape and ac-

40 cordingly the groove formed by the depending flanges 15 and 16 is substantially arcuate in form, the tongue portion 14 on the tooth following along the same curve. The rabble tooth may be brought into or out of engagement with the rabble arm by sliding the tongue member 14 into and out of the groove. A stop member 17 at the end of the groove 45 may be formed as an integral part of the rabble arm housing casting.

50 As indicated in the drawings, the teeth

may be placed at a suitable angle transversely of the rabble arm to obtain the proper rabbling action and accordingly the cooperating joining members 14, 15 and 16 may be placed at a corresponding angle transversely of the 55 axis of the rabble arm. With the stop member 17 located at the side shown in Fig. 1 the direction of travel of the rabble tooth through the ore should be as indicated by the arrow, so that the force of the ore in engagement 60 with the tooth will bring the tongue member 14 up against the stop member.

The cooperating arcuate joining members, 65 together with the stop member, serve to rigidly retain the tooth in the desired working position free from vibration or rocking movements and yet the tooth may be readily removed and is not liable to become jammed or wedged in a manner which might cause 70 the breakage of the parts or prevent renewal 75 of teeth. It is evident that any tendency for lateral movement of the teeth due to pivoting at the tongue and groove joint is eliminated by reason of the arcuate form of this joint. At the same time the tongue and groove joining members substantially conform to the curvature of the under side of the housing so 80 that no heavy thickened or irregular areas are necessary on the rabble arm housing member. A rabble arm of cylindrical cross-section and of great strength, but light in weight, is thus provided. Also the elimination of thickened irregular areas and the like, 85 not only results in a saving in material, but also prevents non-uniform temperature conditions and the consequent destructive forces and strains which tend to arise within heated metal parts of irregular dimensions.

The rabble tooth members are preferably 90 cast from suitable high temperature resisting metal and if desired, the working faces of the teeth may be formed with cavities or other irregular areas as indicated at 18.

The cross-sectional form of the tongue and groove joining members as shown in Figs. 1 95 and 2 may follow a generally rectangular outline, but if desired for manufacturing considerations or for other reasons, other shapes may be used, as for example in Fig. 3, in which the coating joining parts are sub- 100

stantially circular in cross-section. That is, tooth members 19 are provided at their upper edges with rounded beaded or tongue portions 20 substantially circular in cross-section for engaging with corresponding grooves of circular cross-section formed by arcuate flange members as at 21 and 22. As in the construction above described, the flange members 21 and 22 may be cast integral with a rabble arm housing member 23.

The manner in which rabble teeth and rabble arms function in furnaces is disclosed, for example, in the patent to Herreshoff, 976,175, of November 22, 1910. That is, the rabble arms are designed to move over furnace hearths in a generally parallel relationship thereto, whereby the rabble teeth gradually advance the material under treatment from one part of the hearth to another.

While the invention has been described in detail with respect to particular preferred examples which give satisfactory results, it will be understood by those skilled in the art, after understanding the invention, that various changes and modifications may be made without departing from the spirit and scope of the invention, and it is intended therefore in the appended claims to cover all such changes and modifications.

What is claimed as new and desired to be secured by Letters Patent of the United States is:

1. The combination with a furnace rabble arm presenting an exterior, substantially arcuate surface facing downwardly at all times and movable in the sense that a given point thereon follows a circular path centered at one end of said arm, of a rabble tooth secured to said exterior surface of said rabble arm by relatively slidable tongue and groove sections integrally formed, respectively, with said arm and tooth, said sections being each substantially arcuate in form in correspondence with said arcuate surface.

2. The combination with a furnace rabble arm presenting an exterior, substantially arcuate surface facing downwardly at all times and movable in the sense that a given point thereon follows a circular path centered at one end of said arm, of a rabble tooth secured to said exterior surface of said rabble arm by relatively slidable tongue and groove sections integrally formed, respectively, with said arm and tooth, said sections being each substantially arcuate in form in correspondence with said arcuate surface, said rabble tooth being disposed at an angle with respect to its direction of movement.

3. The combination with a furnace rabble arm presenting an exterior, substantially arcuate surface facing downwardly at all times and movable in the sense that a given point thereon follows a circular path centered at one end of said arm, of a rabble tooth secured to said exterior surface of said

rabble arm by relatively slidable tongue and groove sections integrally formed, respectively, with said arm and tooth, said sections being each substantially arcuate in form in correspondence with said arcuate surface and being disposed and retaining said rabble tooth at an angle with respect to its direction of movement.

4. The combination with a furnace rabble arm presenting an exterior, substantially arcuate surface facing downwardly at all times and movable in the sense that a given point thereon follows a circular path centered at one end of said arm, of a rabble tooth secured to said exterior surface of said rabble arm by relatively slidable tongue and groove sections integrally formed, respectively, with said arm and tooth, said sections being each substantially arcuate in form in correspondence with said arcuate surface and retaining said rabble tooth at an angle with respect to its direction of movement, and an abutment defining one end of said groove to limit movement of said rabble tooth with respect to said rabble arm.

In testimony whereof I have signed my name to this specification.

GEORGE E. CONNOLLY.
